SEAMING MECHANISM

Willy Diezel, Fairfield, Conn., assignor to The Max Ams Machine Company, Bridgeport, Conn., a corporation of Connecticut

Application May 27, 1943, Serial No. 488,639

8 Claims. (Cl. 113—24)

This invention relates to seaming machines for uniting container-ends to container-bodies, especially those made of very heavy-gauge stock, rather than those made of thin sheet material such as is used in the ordinary tin can. The main object and feature of the invention is to provide means for exerting the adequate pressure necessary to bend or deflect such heavy-gauge stock during the seaming operation.

In the accompanying drawings the invention is disclosed in several concrete and preferred forms in which:

Fig. 1 is a view in side elevation of the seaming mechanism of the invention applied to the seaming of irregular shaped containers;

Figs. 2, 3 and 4 are fragmentary sectional views showing the steps of seaming a container-end to a container-body;

Fig. 5 is a vertical sectional view substantially on the plane of irregular line 5—5 of Fig. 6;

Fig. 6 is a horizontal sectional view substantially on the plane of irregular line 6—6 of Fig. 5, with parts broken away;

Fig. 7 is a bottom plan view looking in the direction of arrow 1 of Fig. 5;

Figs. 8, 9 and 10 are more or less diagrammatic views of the parts shown in Fig. 7, disclosing the different position of the parts during the operation of the machine, looking from the top of the parts;

Fig. 11 is a fragmentary detail view of one of the seaming and associated elements shown in Figs. 7 to 10 inclusive;

Fig. 12 is a fragmentary vertical sectional view showing a modified form of the invention;

Fig. 13 is a vertical sectional detail view substantially on the plane of line 13—13 of Fig. 12;

Fig. 14 is a detail view looking in the direction of arrow 14 of Fig. 12;

Fig. 15 is a view similar to Fig. 7 but showing a modified form of the invention as applied to the seaming of a circular container;

Fig. 16 is a view similar to Figs. 7 and 15 but showing a still further modified form of the invention for use in connection with the seaming of a circular container; and

Fig. 17 is a view partly in elevation and partly in section substantially on the plane of line 17—17 of Fig. 16.

Referring first to the form of invention shown in Figs. 1 to 11 inclusive, 30 indicates a container-body and 31 the end or cover to be seamed to the container-body. 32 indicates a chuck to press the end or cover against the container-body, said body being supported by a pedestal (not shown)

or otherwise, in a manner familiar in the art. 33 denotes the seamer head, supporting the seaming mechanism, and 34 is the cam for effecting in-and-out movements of the seaming tools. In accordance with well-understood practice, the work-piece to be acted upon (here the container and its end) and the seamer head are rotated one with respect to the other, the construction used, in the present instance, being that chuck 32 and the work-piece stand still and that seamer head 33 is rotated as by means of gear 35. Seamer head 33 and cam 34 are given one effective revolution with respect to each other during each cycle of movements of the machine, and this is accomplished, in the present instance, by driving the cam, 34, by means of a gear 36 having a different number of teeth as compared with 35, all of which is familiar to those skilled in the art.

10 In the present instance, four seaming-tool assemblies are shown, two of which, 37, carry first-operation seaming rollers and, the other two of which, 38, carry second-operation seaming rollers but, as all the seaming-tool assemblies are substantially alike, only one will be described in detail. Each seaming-tool assembly is constructed as follows: Bolted to seamer head 33, as by means of bolts 39, is a main bearing 40. 41 indicates a seaming-roller arm having a seaming roller 42 at one end, and pivotally mounted at its other end in said bearing 40. The pivotal mounting is here provided by a sleeve 43 oscillatable within said main bearing, said oscillatable sleeve 43 and said seaming-roller arm 41 being preferably integral. 44 is a reciprocatory plunger slidable within sleeve 43 and which, by a thrust movement due to its reciprocation, in a manner to be presently described, causes sleeve 43 and arm 41 to swing to bring seaming roller 42 into and out of engagement with the work-piece. Suitable means are provided to reciprocate plunger 44 from cam 34, which means, in the present instance, are as follows: Carried by seamer head 33 is a bearing bracket 45 supporting a rockshaft 46 that carries a yoke composed of two arms 47. Said arms 47 are provided with rollers 48 that engage in grooved member 49 of reciprocating plunger 44, and one of said arms 47 further carries a cam roller that engages in a cam groove of cam 34. In the case of the first-operation seaming tools, this cam roller is denoted by 50 and engages with inner cam groove 51 of cam 34, and, in the case of the second-operation seaming tools, the cam roller is denoted by 52 and engages the outer cam groove 53 of cam 34. It will

be apparent that rotation of cam 34 will cause plunger 44 to reciprocate within sleeve 43. 54 is an abutment lever, having one end 55 supported or anchored independently of main bearing 40, sleeve 43 and arm 41, but having its middle portion 56 pivotally connected at 57 to intermediate portion 58 of arm 41, and its other and free end 59 extending adjacent to bearing 40 and sleeve 43. Suitable means are provided to transmit the lengthwise thrust of plunger 44 to free end 59 of abutment lever 54 which, in this instance, take the following form: Mounted to move or slide radially, or substantially so, of sleeve 43 is a thrust-member 60 to which is pivotally connected one member 61 of a toggle, the other member of which is indicated by arms 62 pivotally supported on pin 63 of the sleeve. 64 indicates two links pivotally connected at 65 to the lower end of plunger 44, and also pivotally connected at 66 to toggle members 61 and 62. It will now be apparent that, when plunger 44 descends, the toggle is straightened, thereby moving thrust-member 60 against free end 59 of abutment lever 54, and that said abutment lever, being anchored at 55 independently of main bearing 40, sleeve 43 and arm 41, but connected to arm 41 at 57, will swing sleeve 43 (also plunger 44) in main bearing 40 and, thereby, arm 41 to cause a movement of seaming roller 42 into engagement with the work-piece. It will be observed that the thrust thus exerted can be a powerful one, owing to the presence of the toggle, and that the counter-force exerted by the abutment lever is wholly absorbed by the toggle members, when in their straightened position, and will not be transmitted to cam rollers 50 or 52 and grooves 50 or 51 in which they operate. It will also be seen that, by mounting seaming-roller arm 41 in main bearing 40, through which power is transmitted from cam 34, a very rugged support is afforded for arm 41, and said arm 41 can be made long and powerful. Pin 63 is preferably made in the form of a shear-pin so that, in case the machine becomes jammed, this pin will break and, as it is very accessible, it can be easily and quickly replaced.

Lever 54 has, in the preceding description, been referred to as an "abutment" lever, and has been treated as if its anchor, or fulcrum, indicated at 55, were a permanently fixed point. But, one of the advantages of this construction is that 55 need not be a permanently fixed point, and that therefore the construction can be used both for circular and irregular shaped containers. In the event that an irregular shaped container is to be seamed, the abutment lever becomes, in addition, a follow-cam lever and 55 will then, as shown, be a cam roller engaging a follow-cam 67, and the seaming rollers will therefore not only move in and out but will, on account of connection 57 between lever 54 and arm 41, also follow the contour of the container. Lever 54, however, remains an "abutment" lever because it is confined at all points by the walls of the follow-cam. Follow-cam 67 is here stationary with chuck 32 and is of substantially the same contour as the container and chuck face 68.

The shape or contour of the container-body and cover is indicated by the rectangular shape of chuck face 68 (Fig. 7), and it will be noted that the corners of the rectangle present relatively sharp bends. This has long presented a difficulty which, however, could be ignored so long as the sheet material acted upon was rela-

tively thin. It has therefore been the custom, when a follow-cam is used, to have the centers of the seaming roller and the follow-cam roller coincident during the seaming operation. But, when operating upon heavier-gauge sheet metal, as is here contemplated, the tendency to jam at the sharp corners increases, and it has been found that this tendency can be minimized by making the cam groove of the follow-cam of a larger outline than, but of substantially the same contour as, the container and cover, and by providing it with bulges 69 and with gradually tapering portions 70. This enables follow-cam roller 55 and the seaming roller to go around the corners of the rectangle more gradually and easily, even though it necessitates bringing the axes of the seaming roller and the follow-cam roller out of alignment during the seaming operation, a condition heretofore considered undesirable. Although this feature has been found highly advantageous, it is not intended to limit the invention, in all of its aspects, thereto.

The general operation of the machine will be apparent from Figs. 2 to 4 and Figs. 8 to 10, in which latter the center line of follow-cam 67 is indicated by a dotted line. In Fig. 8, the parts are shown with the seaming rollers in neutral position, and, while in such neutral position, the work-piece is introduced into position. See also Fig. 2. The first-operation seaming-tool assemblies 37 now come into operation, as shown by Figs. 3 and 9, and thereafter withdraw, whereupon second-operation seaming-tool assemblies 38 are brought into play, as shown by Figs. 4 and 10.

In Figs. 12, 13 and 14, is shown a modified form of the invention, so far as the means for actuating the plunger inside the main bearing and the means for transmitting its thrust to the abutment lever are concerned.

As there shown, the main bearing is indicated at 71 and the oscillatable sleeve member is denoted by 72. This sleeve carries a seaming-roller arm 73 formed integral therewith. 74 is a reciprocatory plunger, having a cam face 75 that engages thrust-member 76, here taking the form of a ball, which thrust-member engages the free end of abutment lever 77. Plunger 74 has an extension 78 that slides in a guide 79 secured to seamer head 80 by means of bolts 81, and said extension 78 carries a cam roller 82 that (in this instance) engages cam groove 83 in cam 84. The operation is the same as that previously described in connection with Figs. 1 to 11 inclusive and, it will be noted that, when the plunger is in the down position (during the seaming operation), the portion marked 85 of cam face 75 receives the counter-thrust of the abutment lever and that none of this thrust is transmitted back to cam groove 83.

To indicate the flexibility of the machine, attention is called to Fig. 15. If it be desired to transform the machine from one acting on an irregular shaped container to one acting on a cylindrical container, it is only necessary to substitute a cylindrical chuck face 86 for the rectangular one shown in Fig. 7, and to substitute a circular follow-cam 87 for the rectangular follow-cam 67 also shown in Fig. 7. As the remaining elements are the same as those shown in Fig. 7, it is unnecessary to again describe the construction or to designate such parts by a new series of numbers.

Attention is now called to Figs. 16 and 17. It will be understood that, if the machine is to act on a circular container, it is not necessary to em-

ploy a follow-cam. In that case, abutment lever 88 is anchored at one end 89 on a support or fulcrum 90 carried by seamer head 91. The remaining construction of the device is the same as that previously described, and need not be re-described except to say that, if it is desired to have the machine adjustable to different diameters of containers, support 90 can be carried by a block 92 slidably adjustable in curved slots 93 of the seamer head.

I claim:

1. In a seaming machine in which a seaming-roller arm has a swinging movement to provide an in-and-out movement of a seaming roller with respect to the work-piece to be acted upon, the combination with a seamer head; of a main bearing, mounted on said seamer head, for a seaming-roller arm; a seaming-roller arm having a seaming roller at one end and pivotally mounted at its other end in said bearing; an abutment lever having one end anchored independently of said bearing and arm, but having its middle portion pivotally connected to the intermediate portion of said arm, and its other and free end extending adjacent to said bearing; a reciprocatory plunger having a lengthwise thrust movement within said bearing; means to lengthwise actuate said plunger; and means to transmit the lengthwise thrust of said plunger against the free end of said abutment lever to thereby cause the latter to swing said arm on its pivotal support in said main bearing.

2. In a seaming machine in which a seaming-roller arm has a swinging movement to provide an in-and-out movement of a seaming roller with respect to the work-piece to be acted upon, the combination with a seamer head; of a main bearing, mounted on said seamer head; a sleeve oscillatable within said bearing; a seaming-roller arm having a seaming roller at one end and having its other end carried by said oscillatable sleeve; an abutment lever having one end anchored independently of said bearing, sleeve and arm, but having its middle portion pivotally connected to the intermediate portion of said arm, and its other and free end extending adjacent to said sleeve; a reciprocatory plunger having a lengthwise thrust movement within said sleeve; means to lengthwise actuate said plunger; and means to transmit the lengthwise thrust of said plunger against the free end of said abutment lever to thereby cause the latter to swing said sleeve, and thereby the arm, in said main bearing.

3. In a seaming machine in which a seaming-roller arm has a swinging movement to provide an in-and-out movement of a seaming roller with respect to the work-piece to be acted upon, the combination with a seamer head; of a main bearing, mounted on said seamer head, for a seaming-roller arm; a seaming-roller arm having a seaming roller at one end and pivotally mounted at its other end in said bearing; an abutment lever having one end anchored on said seamer head, having its middle portion pivotally connected to the intermediate portion of said arm, and its other and free end extending adjacent to said bearing; a reciprocatory plunger having a lengthwise thrust movement within said bearing; means to lengthwise actuate said plunger; and means to transmit the lengthwise thrust of said plunger against the free end of said abutment lever to thereby cause the latter to swing said arm on its pivotal support in said main bearing.

4. In a seaming machine in which a seaming-roller arm has a swinging movement to provide

an in-and-out movement of a seaming roller with respect to the work-piece to be acted upon, the combination with a seamer head; of a main bearing, mounted on said seamer head; a sleeve oscillatable within said bearing; a seaming-roller arm having a seaming roller at one end and having its other end carried by said oscillatable sleeve; an abutment lever having one end anchored on said seamer head, having its middle portion pivotally connected to the intermediate portion of said arm, and its other and free end extending adjacent to said sleeve; a reciprocatory plunger having a lengthwise thrust movement within said sleeve; means to lengthwise actuate said plunger; and means to transmit the lengthwise thrust of said plunger against the free end of said abutment lever to thereby cause the latter to swing said sleeve, and thereby the arm, in said main bearing.

5. In a seaming machine in which a seaming-roller arm has a swinging movement to provide an in-and-out movement of a seaming roller with respect to the work-piece to be acted upon, the combination with a seamer head; of a main bearing, mounted on said seamer head; a sleeve oscillatable within said bearing; a seaming-roller arm having a seaming roller at one end and having its other end carried by said oscillatable sleeve; an abutment lever having one end anchored independently of said bearing, sleeve and arm, but having its middle portion pivotally connected to the intermediate portion of said arm, and its other and free end extending adjacent to said sleeve; a reciprocatory plunger having a lengthwise thrust movement within said sleeve; means to lengthwise actuate said plunger; a thrust member radially movable in said sleeve to engage the free end of the abutment lever; and means to impart a lengthwise thrust movement of said plunger to said thrust member.

6. In a seaming machine in which a seaming-roller arm has a swinging movement to provide an in-and-out movement of a seaming roller with respect to the work-piece to be acted upon, the combination with a seamer head; of a main bearing, mounted on said seamer head; a sleeve oscillatable within said bearing; a seaming-roller arm having a seaming roller at one end and having its other end carried by said oscillatable sleeve; an abutment lever having one end anchored independently of said bearing, sleeve and arm, but having its middle portion pivotally connected to the intermediate portion of said arm, and its other and free end extending adjacent to said sleeve; a reciprocatory plunger having a lengthwise thrust movement within said sleeve and rotatable with said sleeve; means to lengthwise actuate said plunger; a thrust member radially slidable in said sleeve to engage the free end of the abutment lever; toggle arms between said sleeve and thrust member; and a toggle link pivotally connected to said plunger and toggle arms.

7. In a seaming machine in which a seaming-roller arm has a swinging movement to provide an in-and-out movement of a seaming roller with respect to the work-piece to be acted upon, the combination with a seamer head; of a main bearing, mounted on said seamer head; a sleeve oscillatable within said bearing; a seaming-roller arm having a seaming roller at one end and having its other end carried by said oscillatable sleeve; an abutment lever having one end anchored independently of said bearing, sleeve and arm, but having its middle portion pivotally connected to the intermediate portion of said arm,

and its other and free end extending adjacent to said sleeve; a reciprocatory plunger having a lengthwise thrust movement within said sleeve; means to lengthwise actuate said plunger; a ball constituting a thrust member radially movable in said sleeve to engage the free end of the abutment lever; and a cam carried by said plunger to engage said ball.

8. In a seaming machine in which a seaming-roller arm has a swinging movement to provide an in-and-out movement of a seaming roller with respect to the work-piece to be acted upon, the combination with a seamer head; of a main bearing, on said seamer head, for a seaming-roller

5 arm; a seaming-roller arm having a seaming roller at one end and pivotally mounted at its other end in said bearing; a follow cam mounted independently of said seamer head; an abutment lever having one end anchored in said follow cam, having its middle portion pivotally connected to the intermediate portion of said arm, and its other and free end extending adjacent to said bearing; a reciprocatory plunger having a lengthwise thrust movement within said bearing; means to lengthwise actuate said plunger; and means to transmit the lengthwise thrust of said plunger against the free end of said abutment lever.

WILLY DIEZEL.
